Application April 4, 1940, Serial No. 327,742

7 Claims. (Cl. 126—68)

This invention relates to air heaters adaptable for use in confined spaces, and in places where only infrequent attention can be given to their operation,—as, for example, in freight cars during cold weather, and especially refrigerator cars. Experience has shown that railway cars in which fruits and other perishable foods are brought east from the Pacific coast require heating to prevent injurious freezing of such perishables at the high altitudes reached in crossing the mountains, even at times of the year when refrigeration is needed during the rest of the run. On the other hand, there are some railway runs on which heating is not required at any time of the year. As the need for heat is thus temporary or occasional only, many lines prefer not to build heaters into their cars, but to employ "portable" heaters, that are merely set up in cars when needed and removed as soon as the need is over. This not only reduces the capital investment in heating equipment, but facilitates maintenance and repair of the heaters, when not in use, without withdrawing cars from service. A simple type of charcoal-burning portable heater has been used to a considerable extent.

For heaters to be effective in preventing spoilage of perishables by freezing without themselves sometimes producing spoilage by excessive temperatures in portions of the car lading, or under some weather conditions, two things are necessary: adequate air circulation to produce reasonably uniform temperatures throughout the lading, and regulation of the heat according to the general temperature condition in the car. Air-circulating fans or blowers driven by wind-operated rotors on the car roof, or by prime-movers of one kind or another, have not proved satisfactory; for a wind-rotor not only means a substantially permanent installation on the car, but becomes inoperative when the car is standing protected from the wind; while attempts to develop a satisfactory prime-mover meet with difficulty from the necessity of operating the equipment for long periods without attention. Moreover, satisfactory regulation of the heat according to the temperature inside the car is complicated by the desirability of locating the temperature-responsive control or thermostat at a distance from the most suitable location for the heater.

In suitable forms of embodiment, such as hereinafter described, the heater of my invention combines effective air circulation and heat regulation, without the necessity for mechanical circulating means, with simplicity and portability

comparable to that of the ordinary charcoal-burning heater. The heater can be placed in one end of a freight-car, or in the usual ice-compartment or bunker of a refrigerator car, and can be arranged to draw cool air effectively from the bottom of the car, where it naturally gravitates, and to deliver the heated air to the top of the car; while the thermostatic control can be located anywhere in the car that is found most suitable or convenient. Other features and advantages of the invention will appear from the following description of species and forms of embodiment, and from the drawings. All the features and combinations shown and described are of my invention, so far as novel.

In the drawings, Fig. 1 is a diagrammatic, longitudinal sectional view of one end of the body of a refrigerator car and its ice bunker, with a heater of a type conveniently embodying the invention in place in the bunker, and with a thermostatic control for the heater mounted at a favorable position in the body of the car; and Fig. 2 is a fragmentary plan view showing the car body and the ice bunker in horizontal section, as indicated by the line and arrows II—II in Fig. 1, but showing a somewhat different heater.

Fig. 3 is a side view of a heater generally similar to that shown in Figs. 1 and 2, on a larger scale, the upper portion of the casing being shown broken away and in vertical section; Fig. 4 is a vertical sectional view (with an intermediate portion of the heater broken away and omitted), taken as indicated by the line and arrows IV—IV in Fig. 2; Fig. 5 shows a vertical section through the heater at right angles to Fig. 3, taken as indicated by the line and arrows V—V in Fig. 3; Fig. 6 is a vertical sectional view at right angles to Fig. 4, taken as indicated by the line and arrows VI—VI in Fig. 4; and Figs. 7, 8, 9 and 10 are plan views with the heater in horizontal section as indicated by the correspondingly-numbered lines and arrows in Fig. 5, but turned 180° from the position of Fig. 5,—portions being broken away and omitted in Figs. 7 and 10.

Fig. 11 is a wiring diagram illustrating the automatic thermostatic and electrical control of the heater.

Fig. 1 shows a section through one end of a freight-car, of an ordinary refrigerator type, with a transverse bulkhead or partition 14 separating a compartment 15 at one end of the car, which during refrigeration serves as the ice-bunker, from the main lading-space 16. The partition 14 is shown provided with the usual grated lower and upper openings 17, 18 for the circulation of

air between the bunker 15 and the lading-space 16, and the walls surrounding the bunker 15 have the usual lining 19, secured to uprights 21 associated with the car body end 20 and with the 5 partition 14, and shown as of perforated sheet metal. The lading-space 16 is shown equipped with the usual slotted lading-deck 22, consisting of transverse boards (with appreciable cracks for the passage of air between them) secured to longitudinal stringers 24 that rest on the car body floor 25, and divide the space under this deck 22 into longitudinal air-ducts 27. As shown, these floor-ducts 27 communicate freely at 28 with the bottom of the ice-bunker 15, beneath the grating 16 in the lower opening 17.

As shown in Figs. 1 and 2, a couple of sections, at least, of the usual ice-grates 29 in the bunker 15 are preferably removed, so that the air heater rests directly on the car floor 25. As shown in 20 Fig. 1, this heater not only heats the air entering the compartment 15 by external radiation and conduction,—thus producing a general circulation up through the bunker 15, to the right in the top of the lading space 16 and then downward, 25 and to the left in the bottom of the lading space and underneath the deck 22,—but also draws in cold air from the longitudinal ducts 27 under the deck 22 and delivers or discharges the heated air into the upper part of the compartment 15, to 30 pass through the opening 18 into the top of the lading-space, thus producing a more powerful circulation in the same general direction. For this purpose, the lower end of the heater casing or shell 30 is provided with lateral intakes comprising flexible conduits 34 that can readily be inserted through the opening 28 under the partition 14 into the air ducts 27, as shown in Fig. 2, and the upper end of the casing is freely open upward at 35, though preferably protected by a 35 grating or the like such as a woven wire screen 36. Preferably the heater is removably secured in place in the compartment 15, against displacement due to motion of the car, as by chains 37, 37 attached to ears or lugs on the casing 30 and 40 secured to the car structure (as to the lining 19) by hooks 39.

When the heater is used in an ordinary freight-car, without the bulkhead or partition 14, its general arrangement and functioning will be 50 substantially the same.

As shown in Figs. 1, 3, 4, and 5, the heater casing 30 comprises a shallow circular base section 40 and a superjacent cylindrical shell or drum section 41 resting on the top of the base 55 40 and removably secured thereto, as by toggle clamps 42 resembling those often used on trunks and suit-cases. This sectional construction allows the base 40 to be put in place and the conduits 34 to be passed through the opening 28 into the ducts 27 before the drum section 41 is put on and secured. Besides its cylindrical wall in which are secured flanged nipples 43 for the connection of the flexible conduits 34, the base section 40 has a bottom 44 and a sheet metal top ring 45 with an upstanding lip, around which engages (rather loosely) the lower end of the shell 41. Inside the casing 30, and preferably above the hollow base 40, there is a (sheet-metal) combustion chamber 46, closed at the 60 top and bottom, as shown in Fig. 5. This combustion chamber 46 may be attached to the adjacent wall of the drum 41 by a sheet-metal brace 46a. Air for combustion may be supplied to the chamber 46 through an opening 47 in its wall and a corresponding opening 48 in

the wall of the drum 41, connected to the opening 47 by a short intervening duct, Fig. 1, or, as shown in Figs. 5 and 6, through the openings 47a in the combustion chamber wall, the openings 48a in an "inner wall" 49 which forms the 5 real enclosing wall of the drum 41 at this point, and an intervening chamber that is described hereinafter. From the top of the combustion chamber 46, a (sheet-metal) flue 50 for the combustion gases extends through the upper portion of the casing 30. As shown in Figs. 1 and 5, this flue 50 is an up-and-down flue of inverted U-form, with the lower end of one leg 51 connected and opening through the upper wall of the combustion chamber 46, and with the lower 10 end of the other leg 52 connected and discharging laterally through an opening 53 in the wall of the drum 41, or, as shown in Fig. 5, through an opening 53a in the inner wall 49 above referred to. As here shown, the lower end of 20 the flue leg 52 is connected and opens into the upper side of a sheet metal box 56 whose outer side is connected and opens through the drum wall at 53, or, as shown in Fig. 5, through the inner wall 49 at 53a. 25

The burner 57 here shown in the combustion chamber 46 is intended for solid fuel such as coke, charcoal, or charquettes, and has the form of a foraminous sheet metal basket-grate or fire-pot, Figs. 1, 4, 5, and 8. It may be supported 30 by attached legs 58 suitably fastened to the bottom of the chamber, and may be supplied with fuel in any suitable way, as from a magazine 60 above the combustion chamber 46, to be described hereinafter. As shown in Figs. 3, 4, and 8, the 35 side, bottom, and top walls of the chamber 46 extend to the drum wall at one side of the drum 41 and to the chute or hopper-like bottom wall 61 of the magazine 60, and are secured to them. In this side of the drum 41, there is an access-opening with a vertically sliding door 62, having a handle 63. Ordinarily kept closed by gravity, the door 62 may be held open, when desired, by a horizontally swinging stop 64 hinged to the combustion chamber wall just inside the door, 40 as shown in Figs. 6 and 8. For convenience in lighting the fire in the grate 57, there is a metal lighting-cup 65 on a horizontally swinging arm 66 that is hinged to the combustion chamber wall directly opposite the stop 64, as shown 45 in Figs. 6 and 8. To light the fire, the cup 65 is swung out through the open door, as indicated in dot and dash lines in Fig. 8; a couple of ordinary "canned heat" cubes are placed in it and lighted; and it is then swung back to an approximately central position under the burner 57. 50

As shown in Figs. 3, 4, 9, and 10, the fuel magazine 60 in the upper portion of the drum 41, above the combustion chamber 46, is located 60 in the opposite side of the drum from the U-flue 50, and is defined by a vertical, longitudinal sheet-metal partition 70 that extends across the interior of the drum 41, nearly diametrically thereof, alongside and closely adjacent both the 65 flue legs 51, 52, parallel with them. As shown in Figs. 4, 5, and 10, the U-flue 50 may be connected to the partition 70 and to the drum wall by bracket plates 71, and thus braced. As shown in Figs. 4, 6, 9, and 10, the sheet-metal hopper 70 bottom 61 of the magazine 60 is attached at its upper, outer margins to the partition 70 and to the wall of the drum 41. As shown in Figs. 2, 3, 4, the magazine 60 has a top wall provided with a charging opening that is normally closed 75

5 by a cover 73. As shown in Figs. 4 and 6, the fuel discharge or delivery opening 74 from the magazine 60 into the combustion chamber 46 is controlled by a swinging gate 75 attached to a horizontal pivot and operating shaft 76, which shaft is mounted in bracket ears 77 secured to the hopper bottom 61, and extends out to the left (Fig. 6) through the wall of the combustion chamber 46 and the adjacent inner wall 49, 10 already mentioned. Fast on the outer end of the shaft 76 is a crank-arm 78, which is connected by a link-rod 79 to one arm of an actuating lever 80 fulcrumed on a pivot-pin 81 that is mounted in brackets 82, 83 secured to the 15 aforementioned partition 49. The lever 80 may be actuated by means connected to its other arm, as hereinafter described.

As shown in Figs. 3, 5, 8, 9, and 10, the inner wall 49 extends vertically in the drum 41, along- 20 side and parallel with the side wall of the combustion chamber 46 and upward above said chamber, nearly to the upper end of the drum. It thus defines within the general outline of the drum 41 a shallow lateral compartment or cham- 25 ber 85, which below the bottom of the magazine 60 is a circular segment in horizontal section, but above that point is abbreviated to approximately triangular form by the partition 70. The upper and lower ends of this compartment 30 85 may be closed off from the interior of the drum 41 by horizontal plates 86, 87 attached to the inner wall 49, to the outer drum wall, and (in the case of the plate 86) to the partition 70. Alongside the combustion chamber 35 46, the inner wall 49 is connected to the combustion chamber wall by horizontal and vertical Z-bars 88, Figs. 5, 6, and 8, which with the other walls form a narrow, closed connecting air-cham- 40 ber 89 alongside the combustion chamber 46, wherein the air for combustion is preheated by 45 radiation and conduction from the combustion chamber.

As shown in Fig. 3, the compartment 85 is almost completely open at its outer side, by virtue of a longitudinal opening in the sheet metal of the drum 41 that corresponds in width 50 to the upper part of the compartment 85, above the bottom of the magazine 60. However, this opening may normally be closed by a detachable cover plate 90, Figs. 5, 8, 9, 10. As shown in Figs. 8, 9, 10, there are groups of holes 91, 92 in the cover plate 90 near the lower end of the chamber 85 and at the level of the gas outlet opening 53a to permit intake of combustion air 5 for the chamber 46, and discharge of gases from the flue 50.

In the operation of the heater, the air entering the base section 40 by the ducts 34 and ascending through the casing substantially surrounds the combustion chamber 46 (with the laterally adjacent air-intake chamber 89) and the combustion gas flue 50, in a comparatively thin stream. But though the air stream is thus spread out thin in its passage upward in the casing 30, the channel is free and unconstricted, and so large volumes of air can pass through with little resistance. Accordingly, the air is rapidly and thoroughly heated (by radiation and conduction from the combustion chamber and the flue), without opportunity for any "channeling through" that might allow large volumes of air to escape being heated. The flow is therefore ample and vigorous. Furthermore, the air stream is agitated and repeatedly mixed up by the changes in shape of the pas-

sage through the casing 30 (at the top of the combustion chamber 46, and at the bend of the U-flue 50), so that the large, rapid stream is issuing from the top of the heater is of comparatively even temperature, without any over- 5 hot portions that might reach the lading space and locally damage the lading.

The descent of the gases of combustion against gravity through the down leg 52 of the U-flue 50 restrains or slows up the flow sufficiently to 10 give opportunity for transfer of the heat of the gases to the ascending air in the casing 30; yet the flue passage is large enough to avoid any serious frictional resistance to the flow, and the flue wall-surface is ample for transmitting 15 the heat of the gases to the air. Thus the flue gases are of moderate temperature when they issue from the outlet 53 or 53a (and the openings at 92) about at mid-height of the heater, 20 and at a comparatively low level in the compartment 15, and are cooled down to a perfectly safe temperature by the time they rise to the top of the car, by mixing with the air that rises around the heater, as well as by radiation and conduction into this air. Finally, the warm 25 air and gases ascending from around and inside the heater are agitated and further mixed together in the top of the car, and especially by their change of direction to pass to the right 30 into the lading space.

It will be apparent, from the foregoing description, that there is a closed channel for air and combustion gases from the air intake at 48 or 48a through the combustion chamber 46 and the flue 50 to the flue gas discharge at 53 or 53a, so that the combustion of fuel and the heating of the air passing around and through the casing 30 can be controlled by throttling or shutting off the air or gas flow at any point of this channel, as well as by controlling the 35 delivery or flow of fuel from the magazine 60 to the burner 57. As here shown, provision is made for controlling and regulating the intake of air at 48 or 48a, the discharge of products of combustion at 53 or 53a, and the supply or 40 flow of fuel from the magazine 60, or any two of them, or even just one of them, by means of vertically movable gate-dampers 93, 94 or 93a, 94a for the openings 48 or 48a and 53 or 53a (shown in Figs. 3 and 5 as sliding in guide 45 ways on wall 49), besides the vertically-swinging fuel gate 75 for the magazine outlet 74, already described. As a convenient operating means for these controls, there is an upright, lengthwise-movable rod 95 which is mounted 50 alongside the drum 41, Fig. 1, or in the compartment 85, Figs. 3, 5, 8, 9, and 10, and has laterally projecting actuating arms 96, 97 to which the dampers 93, 94 are attached or connected, and also an actuating connection (preferably of yielding character) for the fuel-gate 60 lever 80. As shown in Figs. 3 and 5, this latter actuating connection comprises a couple of helical tension springs 98, 98 connected between the end of the lever 80 and upper and lower 65 bracket-arms 99, 99 attached to the rod 95. The arms 96, 97, 99, 99 may be secured to the rod 95 by set-screws, as shown, so that any of them can be adjusted along the rod to secure the desired operation of the control dampers 70 93, 94 or 93a, 94a and the fuel gate 75, or even disconnected, or set in inactive positions, so as to prevent operation of any of these controls.

The motor means here shown for shifting the rod 95 up and down, to actuate the dampers 75

93, 94 or 93a, 94a and the gate 75, comprises electro-motive means consisting of oppositely-acting solenoids 101, 102 through which the rod extends, and for which it has suitably enlarged core parts 103, 104. These solenoids 101, 102 are mounted on a common base which is itself mounted on the drum 41 of the casing 30 in Fig. 1, or on its inner wall 49 in Figs. 3, 5, and 10. The solenoids 101, 102 and cores 103, 104 serve 10 as guides for vertical sliding movement of the rod 95; and as shown in Figs. 3 and 5, there is also a guide bracket 105 for the lower part of the rod, mounted on the wall 49 between the arms 99, 99. As shown in Figs. 3 and 5, the 15 rod 95 carries stop projections 106, 107 above the upper solenoid 101, for engaging and actuating the vertically swinging operating arm of a three-pole snap switch 108 mounted on the wall 49 alongside the rod, as explained hereinafter.

20 With suitable design and proportioning of the parts (including the linkage 18, 19, 80 for connecting the fuel-gate 75 to the rod 95) the gate 75 can be made to approximately balance the weight of the rod 95 and the dampers 93, 25 94, etc., in all positions of the mechanism. This not only minimizes the power required in the solenoids 101, 102 to operate the mechanism, but means that the latter is so nearly stable in all positions that friction suffices to "keep it put" 30 without any energization of either solenoid. The movement of the rod 95 is limited by the action of the solenoids 101, 102 themselves.

As shown and indicated in Figs. 1 and 11, the solenoids 101, 102 and the switch 108 are connected, through a (three-wire) flexible cable or cord 109, to the electro-thermostatic control unit 110, which need not necessarily be located in the compartment 15, but may be located at a favorable position in the lading-space 16, if 40 the lading permits of placing it there: e. g., suspended from the roof near the middle of the car, as in Fig. 1, which also shows an additional cable 109a for connecting this same control unit 110 to another similar heater in the other end 45 of the car (not shown). As shown in Fig. 11, the control unit 110 comprises a bellows-type thermostat 111 pivotally connected to one arm of a rocking lever 112 whose other forked arm 50 coacts with adjustable stop-screws 113, 113 and actuates the vertically swinging operating arm of a snap-switch 114 (similar to the switch 108), through adjustable abutment-screws 116, 116 in the forked arm. The switches 108, 114 may be connected in circuit with the solenoids 101, 102 55 and with a suitable source of voltage and current (such as a series of dry-cells 122) as shown, in a manner well understood by electricians.

Assuming that the parts are in the positions shown in Figs. 1 and 11, and that the thermostat 60 111 expands with a rise of temperature in the lading space 16, the lever 112 is rocked counter-clockwise to throw the switch 114 and energize the lower solenoid 102, thus depressing the rod 95 and closing both dampers 93, 94 or 93a, 94a 65 and the fuel feed gate 75, as shown in Figs. 3 and 5, and also finally throwing the switch 108 to break the circuit and deenergize the solenoid 101. If, subsequently, the temperature in the lading space 16 falls sufficiently, the contraction 70 of the thermostat 111 throws the switch 114 back to the position shown in Fig. 11 and energizes the upper solenoid 101 to lift the rod 95 and open the dampers 93, 94 or 93a, 94a and the fuel-feed gate 75 as shown in Figs. 3 and 5, also finally 75 throwing the switch 108 back to its position in

Fig. 11, and thus breaking the circuit and deenergizing the solenoid 102. Thus electrical energy is only used while the rod 95 is actually being shifted.

The yielding connection afforded by the springs 5 98, 98 not only takes care of the lateral shift of the end of the lever 80 to which they are connected, but also allows the rod 95 to complete its movement (either way) when one of the solenoids 101, 102 is energized, notwithstanding any 10 impediment to the movement of the fuel gate 75. If, therefore, a large lump of fuel should resist the closing of the gate 75, the spring tension will bring about a reverse motion of the gate, and a series of opening and closing movements of 15 the rod 95 and the gate 75 will follow, until the obstruction is dislodged thereby, and the gate is substantially closed.

While control of the air intake and the flue draft as well as the fuel feed represents the 20 most complete control of the heater, one or two of these controls are in many cases sufficient. For a single control, that of the flue-draft (at 53 or 53a) is generally to be preferred.

Having thus described my invention, I claim: 25

1. An air heater comprising an upright casing, with cool air intake means at its lower end and heated air delivery at its upper end; a combustion chamber in the lower portion of said casing, substantially surrounded by air ascending 30 through the casing; a fuel magazine at one side of said casing, above said combustion chamber, for supplying fuel by gravity to the latter; and an inverted U-flue in the other side of said casing above the combustion chamber, with both 35 its legs adjacent and alongside said fuel magazine and surrounded by the air ascending through the casing, one of said legs communicating at its lower end with the combustion chamber, and the other discharging the combustion gases at its 40 lower end through the side of the casing.

2. An air heater comprising an upright casing with cool air intakes at its lower end comprising flexible air conduits extending laterally from the casing, and with heated air delivery at its upper 45 end; a combustion chamber mounted in the lower portion of said casing, above said air intakes, and substantially surrounded by the air ascending from said intakes through the casing; a fuel magazine at one side of said casing, above said combustion chamber, for supplying fuel by gravity to the latter; and a flue in the other side of said casing above the combustion chamber, adjacent and alongside said fuel magazine surrounded by the air ascending through the casing, said 50 flue communicating at one end with the combustion chamber, and discharging the combustion gases at the other end through the side of the casing at a considerable proportion of its height below the heated air delivery at the upper end 60 of the casing.

3. An air heater comprising an upright casing, with cool air intake means at its lower end and heated air delivery at its upper end; a combustion chamber, with a burner therein, mounted 65 in the lower portion of said casing, and substantially surrounded by air ascending through the casing; a fuel magazine at one side of said casing, above said combustion chamber, for supplying fuel by gravity to the latter; a flue in the 70 other side of said casing communicating at one end with the combustion chamber and discharging the combustion gases at its other end; and means forming along the side of said casing a longitudinal compartment laterally overlapping 75

- 5 said combustion chamber and communicating therewith and also extending upward above said combustion chamber, and provided with air intake and smoke outlet means and communicating laterally with the discharge end of said flue.
4. An air heater comprising an upright casing, with cool air intake means at its lower end and heated air delivery at its upper end; a combustion chamber, with a burner therein, mounted in the lower portion of said casing, substantially surrounded by air ascending through the casing, and having air-intake means; a fuel magazine at one side of said casing, above said combustion chamber, for supplying fuel by gravity to the latter; a flue in the other side of said casing communicating at one end with the combustion chamber, at its other end discharging the combustion gases from the casing; said combustion chamber and flue forming a closed channel for air and combustion gases; damper means for controlling the air and gas flow through said channel; a gate for controlling the feed of fuel from said magazine to said burner; an upright operating rod mounted alongside said casing for up and down movement, and having actuating connection to said damper means; and means forming a yielding actuating connection between said rod and said fuel control gate, so that movement of the rod may take place when movement of the gate is blocked by fuel.
- 30 5. An air heater comprising an upright casing, with cool air intake means at its lower end and heated air delivery at its upper end; a combustion chamber, with a burner therein, mounted in the lower portion of said casing, substantially surrounded by air ascending through the casing, and having air-intake means; a flue in said casing above said combustion chamber communicating at one end with the combustion chamber, and at its other end discharging the combustion gases through the side of the casing at a considerable proportion of its height below the heated air delivery at the upper end of the casing; damper means for controlling the discharge opening of said flue through the side of the casing; an upright operating rod mounted alongside said casing for up and down movement, and having actuating connection to said damper means; and motor means mounted on said casing for moving said rod as aforesaid.
- 45 6. An air heater comprising an upright casing, with cool air-intake means at its lower end and heated air delivery at its upper end; a combustion chamber, with a burner therein, mounted in the lower portion of said casing, substantially surrounded by air ascending through the casing, and having air-intake means; a fuel magazine at one side of said casing, above said combustion chamber, for supplying fuel by gravity to the latter; a flue in the other side of said casing communicating at one end with the combustion chamber, at its other end discharging the combustion gases from the casing; said combustion chamber and flue forming a closed channel for air and combustion gases; means forming along the side of said casing a longitudinal compartment laterally overlapping said combustion chamber and also extending upward above the same; damper means for controlling the air and gas flow through said channel; a gate for controlling the feed of fuel from said magazine into said combustion chamber to said burner; an upright operating rod movable up and down in said lateral compartment, and operatively connected to said damper means and gate; electromotive means in said compartment for moving said rod as aforesaid; and switch means in said compartment actuated by said rod and controlling energization of said electromotive means.
- 50 7. An air heater comprising an upright casing, with cool air-intake means at its lower end and heated air delivery at its upper end; a combustion chamber, with a burner therein, mounted in the lower portion of said casing, substantially surrounded by air ascending through the casing, and having air-intake means; a flue in said casing above said combustion chamber communicating at one end with the combustion chamber and at its other end discharging the combustion gases from the casing; said combustion chamber and flue forming a closed channel for air and combustion gases; means forming along the side of said casing a longitudinal compartment laterally overlapping said combustion chamber and also extending upward above the same; damper means for controlling the air and gas flow through said channel; an upright operating rod movable up and down in said lateral compartment, and operatively connected to said damper means; and motor means mounted on said casing for moving said rod as aforesaid.
